STAMPING PRESS

Adonias J. Gilbert, Newtonville, and Casper Mehlum, Waltham, Mass.; said Mehlum as signor to said Gilbert

Application March 13, 1947, Serial No. 734,486

9 Claims. (Cl. 164—117)

1

This invention relates to stamping presses for the stamping or punching of strip stock and is directed more particularly to novel and efficient means for feeding strip stock of metal, plastic or other material, to and from stamping or punching dies in such manner that the successive operations of the dies are very accurately spaced longitudinally of the stock.

The primary object of the present invention is to provide a machine for the purposes stated which shall be remarkably simple, yet absolutely accurate and smoothly operating.

Speaking generally, the feed of stock, according to the present invention, is accomplished by a pivoted feeder adapted to be oscillated about fixed pivots and so constructed as to grip the strip stock in one position, feed it forwardly, and then return to the initial gripping position. This feeder has fixed and movable jaws, so constituted that their gripping faces remain substantially parallel to the direction of feed of the stock and this precludes crimping of the stock while in gripping cooperation with the jaws.

The machine of this invention further embodies a holding mechanism for gripping and holding the stock during retrograde movement of the feeder, so as to eliminate idle movement of the strip at any time and to hold the stock stationary as successive portions thereof are acted upon by the dies.

An important feature of the machine of this invention is that it embodies a single operating cam shaft from which single shaft all operating parts of the machine are actuated. This shaft actuates said parts through a series of cams and eccentrics, properly timed so that the parts are operated in proper timed synchronized sequence. The use of a plurality of shafts and a large number of gears heretofore considered necessary in machines of this general character, is thereby rendered unnecessary and much less power is required to operate the machine than heretofore.

Features of the invention, other than those adverted to, will be apparent from the herein-after detailed description and appended claims; when read in conjunction with the accompanying drawings.

The accompanying drawings illustrate one practical embodiment of the invention, but the construction therein shown is to be understood as illustrative, only, and not as defining the limits of the invention.

Figure 1 is a perspective view of the machine of this invention, certain portions of which are broken away in the interest of clearness.

2

Figure 2 is a front elevation of the machine of Figure 1.

Figure 3 is a plan view of the machine.

Figure 4 is an elevation of the machine on a somewhat enlarged scale, as viewed from the right hand end of Figures 2 and 3.

Figure 5 is a section on the line 5—5 of Figure 1.

Figure 6 is a section on the line 6—6 of Figure 1.

Figure 7 is a section on the line 7—7 of Figure 1.

The machine of this invention comprises end frames or standards 1 and 2 which are spaced apart by spacing rails 3, 4, 5, 6, 7 and 8, the opposite ends of which are bolted to the end frames. Supported on the two rails 3 and 4, at one end of the machine, is a table 10 on which is mounted a die couple comprising a fixed die member 11 and a movable die member 12. The movable die member 12 has an upstanding boss 13 to which is secured one end of an operating lever 14. The lever is pivoted intermediate its ends upon a vertically adjustable standard 15 mounted on the table 10, while the other end of said lever is pivoted to an operating eccentric hereinafter described.

Mounted on the rails 3 and 4 at the opposite end of the machine is a table 10a which supports a holder 16. This holder comprises a fixed jaw 17 and a movable jaw 18. The movable jaw is secured to one end of a lever 19 mounted on a pivot 20, while the other end of such lever is secured to a link 21, operated as hereinafter described. Interposed between the table 10a and the power arm of the lever 19 is a spring 22 which normally tends to elevate the power arm of the lever and lower the movable jaw 18 into engagement with strip stock S adapted to be passed between said jaws.

The strip stock S may be conveniently fed from a feed roll F, indicated in phantom at the left of the machine in Figure 2 across and above the tables 10 and 10a to a take-up roll T indicated in the same figure, so that it is uncoiled from the feed roll, stamped or punched during its passage through the machine and then coiled upon the take-up roll T. These rolls F and T may conveniently be in the form of reels, operated in any suitable manner, the belt t being indicated in Figure 3 as a driving means for the roll T and acting upon this roll through a suitable friction clutch (not shown).

Extending horizontally from front to back of the machine is a single cam shaft 23 supported to rotate in bearings 24 carried by the rails 5 and 6 (Figure 3). To the rear end of the shaft 55 is fixed a gear 25 which meshes with a gear 26

carried by a shaft 27. This shaft 27 is mounted in bearings 28 also fixed on the rails 5 and 6. Mounted on the shaft 27, which is in effect a countershaft, is a pulley 29 adapted to be driven by a belt 30 which is in turn driven by a motor 31 which constitutes the prime mover of the machine. The gears 25 and 26 are speed reduction gears, so that the machine may be operated to feed the strip S at a convenient speed. Any other suitable form of drive, such, for example, as a worm and worm wheel might be used to eliminate the speed reduction gearing shown, entirely.

On the cam shaft 23 are fixed three cams 32, 33 and 34 and also an eccentrically mounted disk 35 of an eccentric. The eccentric 35 is embraced by the usual strap 36 connected by a conventional pitman 37 to the power arm of the operating lever 44 which operates the die 12, so that the movable member 12 of the die couple will be raised and lowered with a smooth easy movement. A cam may also be used for this purpose in lieu of the eccentric 35 which may be conveniently referred to as a cam.

The cam 32 is for operating the feeder. It is shown as an eccentrically supported disk adapted to coact with a cam follower 38 mounted on an arm 39. The lower end of this arm is pivoted to a plate 9 supported on rods 9a which extend through the rails 7 and 8, as shown best in Figure 1. The upper end of the arm 39 is connected by a link 40 to the strip feeder presently described. The connection between the link 40 and the arm 39 is shown in detail in Figure 7. Here it will be noted that the link 40 carries a block 41 guided in a vertical slot 42 in the upper portion of the arm 39 and a screw 43 passes downwardly through the top of the slot and through the block 41. By rotation of the screw 43, the block 41 may be raised or lowered to vary the throw of the link 40 and the consequent throw or travel of the feeder.

The feeder comprises two spaced apart parallel arms 44 and 45, each of which is pivoted at its lower end to the plate 9, as shown best in Figures 1, 2 and 5. The link 40 is pivoted to the arm 45 which has a series of perforations, any one of which the pivot of the link 40 may occupy to further the throw of the feeder, as desired.

The arms 44 and 45 extend upwardly to a point above the plane of the table 10 and carry relatively fixed and movable jaws. The fixed jaw 46 is adapted to lie below the plane of the strip S while the movable jaw 47 lies above the strip. The jaw 46 is secured to the arms 44 and 45 by pivots 48 which pivots are at the same elevation, so that, when the arms are oscillated about their lower pivots, they will form with the rail and the fixed jaw 46 a parallelogram, so that the fixed jaw 46 will at all times occupy a horizontal position substantially or slightly below the plane of the strip S. The upper jaw 47 has a depending rigid stem 49 (see Figures 1 and 5) which extends downwardly through an aligned perforation in the lower jaw 46 and has a reduced threaded end 50 terminating in a ball 51. An adjusting nut 52 is screwed onto the threaded stem and acts against a spring 53 which normally tends to lower the upper jaw 47 and cause it to grip the strip S against the lower jaw 46 (Figure 5).

Embracing the ball 51 at the lower end of the stem 50 is a socket formed in the upper end of a push rod 53. The lower end of this push rod makes a ball joint connection 54 with a bracket 55 rigidly secured to the outboard end of a lever

56, pivoted intermediate its ends to and near the lower end of one of the feeder arms 45. The other end of this lever, i. e., the power arm thereof, has a link connection 57 with an arm 58 carrying a cam follower 59 which coacts with the cam 33.

As a result of these trains of mechanism, the cam 33 causes the feeder to be oscillated from the position shown in Figure 1 in a direction to the right thereof. During this so-called forward movement of the feeder, the cam 33 is at its low phase, thereby permitting the spring 53 to lower the upper jaw 47 of the feeder into gripping relation with the strip, so that said strip is fed forwardly a distance controlled by the adjustment of the screw 43 of Figure 7. At the end of the forward movement of the feeder, the high phase of the cam 33 engages the cam follower 59 and acts upon a push rod 53 to disengage the feeder jaws from the strip stock, so that, during a return or retrograde movement of the feeder under the pull of the spring 28a, the strip is released. The timing is such that, during this period, when the strip is released and at rest, the eccentric 35 will act upon the die 12 to effect the stamping or punching operation.

There is apt to be some drag of the feeder on the strip during such retrograde movement and the present invention provides means for holding the strip stationary against this drag to provide for accurate stamping or punching by the die couple. The holder, indicated at 18, performs this function and its movable jaw 18 is controlled by the link 21 hereinbefore referred to. This link is pivoted at its lower end to an arm 60, one end of which, like the arm 58, is pivoted on a fixed rod 61, while the other end of the arm 60 carries a cam follower 62 coacting with the cam 34 (Figure 1). The cams 33 and 34 are set oppositely so that when the high phase of the cam 33 is cooperating with its follower 59 to release the strip stock during the retrograde movement of the feeder, the low phase of the cam 34 will be presented to its follower 62 to permit the spring 22 to cause the jaw 18 of the holder to grip the stock. In this way the stock is immobilized during the punching or stamping operation and the coincident retrograde movement of the feeder.

However, as the high phase of the cam 33 leaves its follower 59 and permits the feeder jaws to grip the stock for the next forward feed thereof, the high phase of the cam 34 engages its follower 62 and lifts the movable jaw 18 of the holder free of the stock to permit the stock to be fed. In this way the parts are synchronized for intermittent co-related operations, successively coacting with one another to intermittently feed and punch the stock. In practice the machine operates smoothly, without appreciable vibration and with practically no noise except that incident to ordinary die operation. The feed is absolutely accurate and uniform.

The strip operated upon by this invention may be used for a wide variety of purposes. For example, we have employed it for the cutting of razor blades from strip stock, in which operation it is convenient to notch the edges of the stock and stamp out holes for the safety razor pins or other holding devices, during continuous operation and thereafter and at some subsequent operation, separate the thus formed blades from the strip stock. Our experience in thus manipulating razor blades has indicated the remarkable accuracy of the machine of this invention.

The foregoing detailed description sets forth the invention in its preferred practical form, but

the invention is to be understood as fully commensurate with the appended claims.

Having thus fully described the invention, what we claim as new and desire to secure by Letters Patent is:

1. A machine for feeding and stamping strip stock comprising: fixed and movable jaws of a die couple, a feeder having relatively fixed and movable jaws normally spring impelled to grip the strip, a single cam shaft, an eccentric on said shaft with operative connections with the movable member of the die couple, a cam on said shaft with an operative connection with the feeder to move the jaws collectively relative to the die couple to feed the strip, and another cam on said shaft with operative connections with the movable jaw of the feeder to release the strip from the grip of the jaws between feeding operations.

2. A machine for feeding and stamping strip stock comprising: fixed and movable jaws of a die couple, a feeder having relatively fixed and movable jaws normally spring impelled to grip the strip, a single cam shaft, an eccentric on said shaft with operative connections with the movable member of the die couple, a cam on said shaft with an operative connection with the feeder to move the jaws collectively relative to the die couple to feed the strip, and another cam on said shaft with operative connections with the movable jaw of the feeder to release the strip from the grip of the jaws between feeding operations, in combinations with a normally spring impelled holder to grip the strip between feeding operations, and another cam on said shaft with connections with the holder to release the strip during feeding operations.

3. A machine for feeding and stamping strip stock comprising: a die couple embodying relatively fixed and movable members between which the strip is fed, a feeder embodying fixed and movable jaws between which the strip extends, a holder embodying fixed and movable jaws between which the strip also extends, said die couple, feeder and holder being arranged in spaced relation longitudinally of the strip, a cam shaft carrying a plurality of cams, operative connections between the die couple and one of said cams, an operative connection between the feeder and another of said cams, and an operative connection between the movable jaw of the feeder and another of said cams, said cams being operable to feed the strip when the die and holder are disengaged from the strip and to disengage the feeder from the strip while the die couple and holder are engaged with the strip.

4. A machine for feeding and stamping strip stock comprising: a die couple, a feeder embodying relatively fixed and movable jaws mounted on parallel arms of equal length pivoted to a fixed support at a distance from the jaws and the fixed jaw being pivoted to the respective arms, a stem on the movable jaw extending through and guided in the fixed jaw and spring impressed to normally close said jaws, a push rod connected to said stem for opening said jaws, a cam, a cam follower cooperating with said cam and mounted on a pivoted arm having link connection with the follower to cause said follower to be moved about its pivotal support for the purpose of feeding the strip, a second cam acting upon a follower having a leverage connection with the push rod to release the strip from the grip of the feeder jaws, and means for retracting the feeder when the strip is thus released, an eccentric connected

to the die couple, and a single cam shaft for supporting and operating both of said cams and the eccentric.

5. A machine for feeding and stamping strip stock comprising: a die couple, a feeder embodying relatively fixed and movable jaws mounted on parallel arms of equal length pivoted to a fixed support at a distance from the jaws and the fixed jaw being pivoted to the respective arms, a stem on the movable jaw extending through and guided in the fixed jaw and spring impressed to normally close said jaws, a push rod connected to said stem for opening said jaws, a cam, a cam follower cooperating with said cam and mounted on a pivoted arm having link connection with the follower to cause said follower to be moved about its pivotal supports for the purpose of feeding the strip, a second cam acting upon a follower having a leverage connection with the push rod to release the strip from the grip of the feeder jaws, means for retracting the feeder when the strip is thus released, an eccentric connected to the die couple, a single cam shaft for supporting and operating both of said cams and the eccentric, a third cam also on said cam shaft having a cam follower, a holder for normally gripping the strip, and connections between the holder and the last mentioned cam follower for releasing the strip while the latter is fed by the feeder.

6. A machine for feeding and stamping strip stock comprising: a cam shaft, an eccentric on said shaft, a lever connected to said eccentric, a die connected to the lever to act upon the strip, a cam on said cam shaft, a cam follower coacting with said cam, a holder controlled by said follower for gripping and immobilizing the strip while it is acted upon by the die, a second cam on said cam shaft having a follower coacting therewith, a pivoted arm on which the latter follower is supported, a link secured to said arm, and a feeder secured to the distant end of said link to feed the strip to the die, a spring for retracting the feeder in the opposite direction, said feeder carrying a pair of relatively movable jaws, and a third cam on the cam shaft with operative connections between it and said relatively movable jaws to cause them to engage and grip the strip and feed the same when the feeder is advanced in one direction and to disengage the jaws from the strip when the feeder is retracted in the opposite direction.

7. A machine for feeding and stamping strip stock comprising: a cam shaft, an eccentric on said shaft, a lever connected to said eccentric, a die connected to the lever to act upon the strip, a cam on said cam shaft, a cam follower coacting with said cam, a holder controlled by said follower for gripping and immobilizing the strip while it is acted upon by the die, a second cam on said cam shaft having a follower coacting therewith, a pivoted arm on which the latter follower is supported, a link secured to said arm, a feeder secured to the distant end of said link to feed the strip to the die, a spring for retracting the feeder in the opposite direction, said feeder carrying a pair of relatively movable jaws, and a third cam on the cam shaft with operative connections between it and said relatively movable jaws to cause them to engage and grip the strip and feed the same when the feeder is advanced in one direction and to disengage the jaws from the strip when the feeder is retracted in the opposite direction, and means for adjusting the throw of the feeder

to vary the length of strip fed at each operation thereof.

8. A machine for feeding and stamping strip stock comprising: a die couple, a lever for operating said couple, a pair of relatively movable jaws for feeding strip stock between the couple, parallel arms mounted on spaced apart pivots on a fixed support and pivoted to one of said jaws with the pivots of the jaws spaced apart the same distance as the pivots of the arms and the pivots on both arms being equally spaced apart, means for oscillating said arms to move the jaws along the path of feed of the strip, means for forcing the jaws together to grip and feed the strip in one direction, and means to separate the jaws during oscillation of the arms in a retrograde direction.

9. A machine for feeding and stamping strip stock comprising: a die couple, a lever for operating said couple, a pair of relatively movable jaws for feeding strip stock between the couple, parallel arms mounted on spaced apart pivots on a fixed support and pivoted to one of said jaws with the

10
5

pivots of the jaws spaced apart the same distance as the pivots of the arms and the pivots on both arms being equally spaced apart, means for oscillating said arms to move the jaws along the path of feed of the strip, a spring normally impelling the jaws together to grip and feed the strip in one direction, and a cam operated push rod to separate the jaws during oscillation of the arms in a retrograde direction.
